LATCHING DEVICE FOR JEWEL BOXES AND LIKE RECEPTACLES

Charles S. Gehrie, Montclair, N. J., assignor to Presto
Lock Company, Garfield, N. J., a partnership

Application September 27, 1954, Serial No. 32,437

Term of patent 14 years

(Cl. D50—7)

Fig. 1

Fig. 3

Fig. 1 is a face view of a latching device for jewel boxes and like receptacles, with its members latched together, showing my new design;

Fig. 2 is a side edge elevational view of the latching device as illustrated in Fig. 1; and

Fig. 3 is a face elevational view of the same, with its members released and separated.

I claim:

The ornamental design for a latching device for jewel boxes and like receptacles, as shown.
